UNITED STATES PATENT OFFICE.

CHARLES J. MARTH, OF ST. LOUIS, MISSOURI, ASSIGNOR TO WAYNE MANUFACTURING COMPANY, OF ST. LOUIS, MISSOURI, A CORPORATION OF MISSOURI.

GEARING.

1,139,695.

Specification of Letters Patent. Patented May 18, 1915.

Application filed July 24, 1912. Serial No. 711,246.

To all whom it may concern:

Be it known that I, CHARLES J. MARTH, a citizen of the United States, residing in the city of St. Louis and State of Missouri, have 5 invented a new and useful Gearing, of which the following is a specification.

This invention relates to gearing and it consists of the novel construction and combination and arrangement of parts, illustrated in the accompanying drawings and hereinafter described and claimed with such particularity as will enable those skilled in the art to which it appertains to make and use the same.

15. An object of the invention is to provide a gearing comprising a support, a shaft mounted in a frame pivoted upon said support, and gearing for driving said shaft, in combination with a support pivoted to the 20 first-named support, and means mounted on said pivoted support adapted to be interlocked with said pivoted frame to hold the pivoted frame above said pivoted support.

Another object is to provide gearing for 25 driving mechanisms to operate on the same work during different stages of its treatment comprising a drive shaft, a vertical shaft, means for imparting an alternating rotary movement to said vertical shaft by the constant rotation of said drive shaft in one direction, an upright shaft, gearing for driving 30 said upright shaft in either direction by the constant rotation of said drive shaft in one direction, a pivotally mounted frame, mechanism in said frame driven by said upright shaft, and a plurality of supports mounted independently of said upright shafts for engaging with said frame to hold said frame in different positions to operate on the same 35 work during different stages of its treatment after said vertical shaft had operated on the work.

Other objects and advantages will be apparent from the following description, reference being made to the accompanying drawings, in which—

Figure 1 is a plan view of a laundry bench embodying my invention and equipped with a washing machine and wringer and clothes 50 receptacles. Fig. 2 is a side elevation from the side A of Fig. 1. Fig. 3 is a side elevation from the side B of Fig. 1. Fig. 4 is a cross sectional view on the line 4—4 of Fig. 2. Fig. 5 is a diagrammatic view showing 55 the wringer adjusted and operating to re-

ceive the clothes from the washing machine and to deliver them to the receptacle C. Fig. 6 is a diagrammatic view showing the wringer adjusted and operating to receive the clothes from the receptacle C, and to deliver them to the receptacle D; and Fig. 7 is a diagrammatic view showing the wringer adjusted and operating to receive the clothes from the receptacle D, and to deliver them to the receptacle E.

The main bench consists of a frame 1 supported by posts or legs 2 which are strengthened and reinforced by cross pieces, and by braces 3. The frame of the bench supports bearings 4 in which are journaled the trunnions 5 of the tub F. The tub F is mounted and arranged upon the frame so that one side thereof may readily be lowered below the other side for purposes of draining off the liquid contents. In accordance with this plan the trunnions 5 are arranged nearer to one side of the tub than the other so that the greater weight of the tub will be on the side which is to be lowered. The tub carries a revoluble member 6 having an arm 7 arranged to engage with a latch member 8 on the frame of the bench in order to hold and support the tub in a level adjustment. The member 6 is revolvably mounted in a bearing 9 and has a handle 10 rigid therewith so that said member 6 may be turned to release the arm 7 from the latch 8 and permit the tub to be tilted or inclined. The tub is provided with a discharge outlet 11 for withdrawing the liquid contents when the tub is inclined, 75 said discharge outlet being closed by a stopper or plug when the tub is in use.

The agitator shaft 12 is geared with a shaft 13, and said shaft 13, through suitable connections 14, is driven by a motor 15 95 which may be supported upon the cross pieces of the bench. The bench supports a sleeve 16 in which is revolvably mounted a shaft 17. The shaft 17 has a beveled gear 18 rigid with its lower end and in constant 100 mesh with two beveled pinions 19 which are loosely mounted upon a shaft 20. The shaft 20 is journaled in bearings supported by the bench and is driven by connections from the motor 15. The shaft 20 may be driven by 105 the connections 14 which lead from the motor 15 to the shaft 13, as shown in Fig. 3. A clutch member 21 is mounted between the pinions 19 and may be moved from one to the other of said pinions by suitable operat- 110

ing connections including the rod 22, the arm 23, connecting said rod with said clutch member 21, and a lever 24 for operating said rod 22. Since the pinions 19 are in mesh with the wheel 18 on opposite sides of the axis of said wheel the direction in which the shaft 17 will be driven will be determined by the adjustment of the clutch member 21. A wringer frame 25 is rigid with a sleeve 26 5 revolubly supported by the shaft 17. The shaft 17 is mounted close to the tub F so that the wringer may be supported in the adjustment shown in Fig. 1 to receive the clothes from the tub F and deliver them into a receptacle C on the opposite end of the bench from the said tub F. The shaft 27 10 supports one of the wringer rolls and has a pinion 28 in mesh with a pinion 29 on the upper end of the shaft 17, so that the wringer may be operated by power transmitted to said shaft 17. The opposite end of the wringer frame is provided with a handle 30 adapted to be manually engaged when it is desired to swing the wringer from 15 one adjustment to another. One side of the wringer frame at the end opposite from the sleeve 26 is provided with a socket 31 in which a lock bolt 32 is slidably mounted. A spring 33 has one end attached to the handle 30 and the other end extending through 20 a slot (Fig. 4) in the socket 31 and connected with the lock bolt 32. The spring 33, therefore, constitutes a support for the lock bolt 32 to prevent said lock bolt from becoming 25 detached and also constitutes means for raising said lock bolt within the socket 31. A tubular post 34 is attached to the bench between the tub F and the receptacle C and when the wringer is adjusted to receive the 30 clothes from the said tub F the lock bolt 32 is engaged within the upper end of the said post 34 thereby firmly locking the wringer against displacement. The post 34 also constitutes a support to strengthen and uphold 35 the wringer frame to relieve the strain from the shaft 17 and the other parts.

The auxiliary bench consists of an upper frame 35 supported on the frame 1 by 40 hinges 36. Posts or legs 37 are hinged to the outer edge of the frame 35, and said posts or legs 37 in connection with the hinges 36 constitute means for supporting and holding the frame 35 in horizontal alignment with the frame 1. The frame 35 45 is arranged to support two receptacles. After the clothes have been delivered by the wringer into the receptacle C, the wringer may be adjusted to receive the clothes from the receptacle C and deliver them to the adjacent receptacle D mounted on the auxiliary frame or bench 35. The frame 25 of the wringer operates above the upper edges of the receptacles so that by disengaging the lock bolt 32 from the post 34 the wringer 50 frame may be swung over the top of the re-

ceptacle C and locked, by means of the lock bolt 32, with a supporting post and brace 38 attached to the bench 1 between the receptacles C and D. The pinions 28 and 29 remain enmeshed in whatever position or adjustment the wringer may be, so that when the wringer is moved from the post 34 to the post 38 the wringer rolls will still be driven by power transmitted from the shaft 17. A post 39 is attached to the auxiliary frame or bench 35 so that the wringer may be locked in engagement therewith in position to receive the clothes from the receptacle D and discharge them into the receptacle E. The wringer remains 55 geared with the shaft 17 in this last adjustment, so that said wringer will be power driven in each of its different positions and adjustments. The posts 38 and 39 are substantially of the same construction and arrangement as the post 34.

In Figs. 5, 6 and 7 I have diagrammatically illustrated different adjustments of the wringer showing the wringer in constant operation by the power mechanism. In Fig. 90 5 the wringer is receiving the clothes from the tub F and delivering them into the receptacle C. The arcuate line indicated by the arrows shows the direction of movement of the wringer frame to its second position 95 or adjustment. The wringer is shown in its second position or adjustment in Fig. 6 and is receiving the clothes from the receptacle C and discharging them into the receptacle D, the arcuate line indicating the movement 100 of the wringer toward its third adjustment. In Fig. 7 the wringer is illustrated in its third adjustment and is receiving the clothes from the receptacle D and discharging them into the receptacle E. In this adjustment one side of the wringer is supported by the post 39 which is upon the hinged auxiliary frame or bench and the wringer is driven by the power mechanism 105 upon the main frame or bench. The arcuate line of arrows in Fig. 7 indicate the course 110 of movement of the wringer toward its original or initial position for receiving clothes from the tub F.

Having thus described my invention what 115 I claim and desire to secure by Letters Patent is—

1. A device of the character described comprising a main support, a drive shaft supported by said support, a vertical sleeve 120 attached to said support, an upright shaft journaled in said sleeve at right angles to said drive shaft and extending above said sleeve, gearing whereby said upright shaft may be rotated in either direction by the 125 continuous rotation of the drive shaft in one direction, a frame bearing upon said sleeve and having one end pivoted upon said upright shaft, a plurality of upright elements mounted on said support at equal distances 130

- from said upright shaft, means for interlocking said frame with said elements, a shaft mounted in said frame, and gearing for driving said last named shaft from said upright shaft, substantially as described.
2. In a device of the character described, a support, a drive shaft carried by said support, a frame pivoted above said support, a plurality of elements mounted on said support at equal distances from the pivot of said frame, means for locking said frame in engagement with said elements, respectively, a shaft in said frame, and means for driving said shaft in either direction by the constant rotation of said drive shaft in one direction, substantially as described.
3. In a device of the character described, the combination of a stationary support, a frame pivotally supported above said stationary support, a shaft in said frame, a plurality of upright elements mounted on said stationary support at equal distances from the pivot of said frame, means for locking said frame in engagement with said upright elements, respectively, a support pivoted to said stationary support, an element on said pivoted support also engageable by said locking means, and means for driving the shaft in said frame from said drive shaft in whatever position said frame may be adjusted, substantially as described.
4. In a device of the character described, a main frame, a drive shaft mounted on said main frame, a frame pivoted above said main frame, upright elements supported by said main frame at equal distances from the pivot of said pivoted frame, an upright element movable into and out of position to be locked in engagement with said pivoted frame, means for locking said pivoted frame in engagement with said upright elements, respectively, mechanism in said pivoted frame, and means for driving said mechanism from said drive shaft in whatever position said pivoted frame and said mechanism may be adjusted.
5. In a device of the character described, a main support, a drive shaft supported by said support, an upright shaft mounted on said support at right angles to said drive shaft, gearing whereby said upright shaft may be rotated in either direction by the continuous rotation of the drive shaft in one direction, a frame pivoted on said upright shaft, a plurality of upright elements mounted on said support at equal distances from said upright shaft, an element movable to and from an upright position, means for interlocking said frame with said first-named elements, respectively, and with said last-named element when the latter is upright, a shaft in said frame, and gearing for driving said last-named shaft from said upright shaft, substantially as described.
6. In a device of the character described,
7. In a device of the character described, a support, a drive shaft carried by said support, a frame pivoted above said support, a shaft in said frame, a transmission shaft driven by said drive shaft, gearing whereby said transmission shaft will drive said shaft in said frame in any position of said frame, a plurality of elements mounted on said support at equal distances from said transmission shaft, a member on said frame arranged to engage with said elements, respectively, to hold said frame in its various adjustments, and means for releasing said member from said elements.
8. In a device of the character described, a support, a drive shaft carried by said support, a frame pivoted above said support, a plurality of elements mounted on said support at equal distances from the pivot of said frame, means for locking said frame in engagement with said elements, respectively, a shaft in said frame, a transmission shaft for driving said shaft in said frame from said drive shaft, and optionally operable means for driving said transmission shaft in either direction by the constant rotation of said drive shaft in one direction, substantially as described.
9. In a device of the character described, a support, a drive shaft carried by said support, a movable frame above said support, a shaft in said frame, a movable support at the side of said first-named support, an element on said movable support for holding said frame above said movable support, and means for driving said last-named shaft from said drive shaft while said frame is held above said movable support, substantially as described.
10. In a device of the character described, a support, a drive shaft carried by said support, a frame pivoted above said support, a shaft in said frame, an element movable into and out of an upright position, means for locking said frame in engagement with said element when said element is in an upright position, and means for driving said last-named shaft from said drive shaft.
11. In a device of the character described, the combination of a stationary support, a frame pivotally supported above said stationary support, an element movable into and out of upright position, means for locking said frame in engagement with said element when said element is in an upright position, and means for supporting said element in position to engage said frame.
12. In a device of the character described, the combination of a stationary support, a frame pivotally supported above said stationary support, a shaft in said frame, a plurality of elements mounted on said stationary support at equal distances from the pivot of said frame, another element movable into and out of upright position and being at the same distance from the pivot of

said frame as said first-named elements when in an upright position, means for locking said frame in engagement with any one of said elements, a shaft in said frame, 5 and means for driving said shaft in any position of said frame.

12. In a device of the character described, the combination of a stationary support, a frame pivotally supported above said stationary support, a shaft in said frame, a 10 plurality of elements mounted on said stationary support at equal distances from the pivot of said frame, another element mov-

able into and out of upright position, means for locking said frame in engagement with any 15 of said elements, and means for driving said shaft in said frame in either direction in whatever position said frame may be adjusted, substantially as described.

In witness whereof, I have signed this 20 specification in the presence of two subscribing witnesses.

CHARLES J. MARTH.
